UNITED STATES PATENT OFFICE.

ALPHONSO S. CAMPBELL, OF WEST MEDFORD, MASSACHUSETTS, ASSIGNOR TO A. S. CAMPBELL COMPANY, OF EAST BOSTON, MASSACHUSETTS, A CORPORATION OF MASSACHUSETTS.

CURTAIN WINDOW.

Application filed April 14, 1923. Serial No. 632,037.

This invention pertains to improvements in curtain windows.

It is among the objects of the invention to provide an attachment of a glass or other 5 transparent medium to a curtain window which is of superior strength and improved appearance.

In the drawings, which show a few preferred embodiments of my invention:

10 Figure 1 is a rear elevation of a curtain window;

Fig. 2 is a section on the line 2—2 of Fig. 1;

15 Figs. 3 through 5 are sections corresponding generally to the section shown in Fig. 2, but showing various modifications of my invention;

20 Figs. 6 and 7 are similar sections, but through one frame element only, showing an intermediate stage of assembling such frame element with its carrying curtain and

Fig. 8 is a section on the line 8—8 of Fig. 7, showing the teeth at the free end of the inner flange.

25 Referring to Fig. 2, I have shown the curtain material 8 concealing one side of the frame by being wrapped at 9 over the inner periphery of the frame, the curtain material providing a cushion 10 interiorly 30 of the frame, against which cushion the glass 11 may lie, though preferably the edge and adjacent portions of both faces thereof are bound with supplemental cushioning material such as the adhesive tape 12. The inner 35 edge of the curtain material, where cut to receive the window, is preferably reversely folded at 10 and gripped between the inner flange 13 and the outer flange 14 of the frame. Such flanges are preferably unitary and

40 of relatively thin pressed metal. The inner flange 13 is preferably serrated at its terminal edge the better to grip the curtain material against an abutting surface pursuant to completion of the assembly of the frame 45 with the curtain material. The flange 14 is connected to an upstanding peripheral flange 15 of sufficient height to provide a lateral abutment for the glass 11 while also providing a support for a preferably continuous glass-retaining and edge-concealing 50 frame portion, shown in Fig. 2 as a stamped metal cover frame 16 reversely bent at its inner periphery to provide a glass-engaging portion 17, while curved inwardly at its 55 outer periphery providing a fastening

flange 18 to underlie a beadlike projection 19 extending outwardly from the upstanding peripheral flange 15. The outer flange 14 is preferably corrugated to provide stiffness to the frame, the corrugations extending generally parallel to the adjacent edge of the glass.

The cover plate 16 is not relied upon primarily to hold the glass in the frame, the glass, or the underlying tape, being cemented 60 to the adjacent cushioning surface 10 of the fabric. Thus the glass supplements the stiffness of the frame.

That embodiment of my invention shown in Fig. 3 is like the disclosure of Fig. 2, 70 except that the bead 19' carries the peripheral flange 15 instead of the contrary arrangement. Also in Fig. 3, the covering frame 16' has a somewhat deeper fastening flange 18', than in Fig. 2, so that the appearance 75 of the curtain window installation as viewed from the cover side is somewhat more finished, there being no ordinarily visible gap between the cover frame and the adjacent curtain material. In those embodiments of 80 my invention shown in Figs. 2 and 3, the cover frames are preferably stamped from a sheet of metal to provide a continuous ring of oblong shape. It is, however, obvious 85 that the shape of the cover frame may be oval, round or of other shape to correspond to the desired shape of the window.

In Figs. 4 and 5, I have shown the attaching beads 30, 31 extending first outwardly then upwardly and then inwardly from the peripheral flange, thereby to provide an inwardly opening recess, groove or channel extending entirely around the frame and of such inside diameter as not to interfere with the assembly of the glass with the frame and curtain material, the recess groove or channel in a plane beyond the glass to admit of the entrance therein of suitable glass-overlying elements which in Fig. 4 are shown as a rod, and in Fig. 5 as of sheet material. These may, as desired, be either continuous or discontinuous, and either compressible, as rubber compounds, or relatively incompressible as metal.

In Figs. 6 and 7, I have shown frame constructions strengthened by separate strengthening strips and differing in this respect from the constructions shown in Figs. 2 through 5. In Fig. 6, the strengthening 105

strip 32 is shown stiffening the peripheral flange 15 and also extending parallel to the outer flange 14, herein shown without corrugations. The strengthening strip 32 may 5 also be provided with a serrated edge 33 to grip the edge of the curtain material and hold it against slippage during the bending down of the inner flange 13 to grip the curtain material. Slippage of the curtain material during this assembling operation may 10 also be opposed by sharp teeth formed on the edge of the flange 13 to grip the material bent over it during the bending operation, as well as to press this material firmly 15 against the upstanding flange 15 or 32, as the case may be, the points of the teeth penetrating the curtain material and absolutely precluding any working loose thereof under ordinary strains.

20 In all of the embodiments of my invention, shown in the drawings, the frame which grips the curtain material is substantially U-shaped in cross-section until after the material is wrapped about the inner flange. 25 Then the flange is pressed outwardly and downwardly to grip the material as previously described.

In Fig. 7, a strengthening strip 32' cooperates with a corrugation 34, teeth 35 on the inner upstanding edge of the strip entering the cloth and assisting in holding it against slippage after the bending down of the inner flange 13.

35 It will be noted that in all embodiments of my invention illustrated, the glass considerably overlaps the frame to provide large bearing area and opportunity for cementing, that the glass may stiffen the frame and vice versa. In each embodiment illustrated, an 40 upstanding peripheral flange is provided, which extends relatively close to the periphery of the glass, stiffening means of one type or another being provided to stiffen the frame, and the various forms of bead for holding the glass-engaging means (cover 16, 45 16' or retainer at 30 or 31) do not extend over the glass and can therefore be of much greater length and of much greater stiffness of construction than where prongs, tabs or 50 the like are bent during assembly either over the glass or over a glass-engaging part.

55 While I have shown preferred embodiments of my invention, I have done so for purposes of clarification and not for purposes of limitation. The scope of my invention is best defined in the appended claims.

Claims:

1. A curtain window installation comprising, in combination, a curtain, a frame member concealed at one side by said curtain, said frame member including inner and outer flanges connected by a bend overlain by said curtain, the curtain fabric being

clamped between said flanges, a glass overlying said inner flange and means for securing said glass in position relative to said frame member and said frame member presenting an upstanding flange abutting the edges of the glass and the inner flange for 65 the purposes set forth.

2. A curtain window installation comprising, in combination, a curtain, a frame member concealed at one side by said curtain, said frame member including inner and outer flanges connected by a bend overlain by said curtain, the curtain fabric being clamped between said flanges, a glass overlying said inner flange and means for securing said glass in position relative to said 75 frame member and said frame member presenting an upstanding flange cooperating with the terminal end of the inner flange to grip securely the curtain fabric therebetween.

3. A curtain window installation comprising, in combination, a curtain, a frame member concealed at one side by said curtain, said frame member including inner and outer flanges connected by a bend overlain by said curtain, the curtain fabric being clamped between said flanges, a glass overlying said inner flange, a second frame member adapted to secure said glass in position, an upstanding flange adjacent to the outer 90 periphery of said frame member and a plurality of teeth at the terminal edge of said inner flange cooperating with said upstanding flange to prevent loosening of the curtain material around said frame after the 95 curtain has been assembled with said frame.

4. A curtain window installation comprising a frame member presenting inner and outer flanges adapted to clamp between them the edges of a curtain carrying said frame member, an upwardly extending flange connected to said outer flange, a glass, and a permanent bead connected to said upwardly extending flange, and removable glass-engaging means on the opposite side of the 110 glass from said frame, said glass-engaging means secured to the said bead for holding the glass in place.

5. A frame forming a part of a curtain window installation and comprising two 115 parts, one part presenting inner and outer flanges adapted to clamp the curtain material between them, an upstanding flange integral with said outer flange, a bead carried by said upstanding flange and the other part 120 providing a removable cover presenting a resilient outer edge adapted to snap over said bead to hold the glass of the installation in place.

In testimony whereof, I have signed my 125 name to this specification.

ALPHONSO S. CAMPBELL.
